2 Claims. (Cl. 19—131)

In the high draught mechanisms for the spinning of cotton in which the rovings are conducted by means of endless belts, there are already in use arrangements or devices for guiding these 5 belts made up of two plates of steel or other material duly separated at a distance slightly greater than the width of the endless belts and conveniently joined together forming a cage or framework.

10 This invention refers to improvements introduced in these guiding devices, with which there is obtained a better guidance of the endless belts and which in addition exercise other functions which improve the working of the machine.

15 These improvements consist in the form and arrangement of the plates of guiding framework, in the arrangement of flanges in the side plates to prevent the slipping off of the belts and in the union of these side plates by means of two cross 20 pieces, one of which limits the swinging movement of the sliver or roving, whilst the other acts as a cleaner of the lower belt.

25 In the attached drawing there is shown several forms of execution of the improvements of this invention.

30 Figures 1 and 2 represent respectively a side elevation and a cross section through the line II—II of the Figure 1, of a pair of cylinders with their corresponding endless belts and the guiding framework of the belts.

35 Figs. 3 and 4 represent a longitudinal section through the line III—III and a cross section through the line IV—IV of a guide framework provided with interior flanges.

40 Figure 5 is a side elevation of a framework with the back joining piece arranged to limit the swinging movement of the roving and Figure 6 is a back elevation of this same framework mounted on the cylinders and the belts and

45 Figures 7 and 8 are respectively a side view partly in section and a front elevation looking in the direction of the arrow VIII of a guiding framework with the lower crosspiece which acts as a belt cleaner.

50 As is seen in the Figures 1 and 2 the guiding device is constituted by two side plates 1 of sheet metal conveniently joined together forming a cage or framework. These side plates 1 are adapted to the collars or parts of lesser diameter 4, 5 of the cylinders 2, 3 and encircle laterally almost completely the whole formed by the bodies or parts of greater diameter 2, 3 of these cylinders and by the belts 6, 7 applied upon them, in this way preventing the introduction of fluff or dust 55 between the belts and the cylinders.

The two plates 1 are arranged separated one from the other at a distance slightly greater than the width of the bodies 2, 3 of the cylinders and the width of the belts 6, 7 but sufficiently adjusted on the cylinders in order that the belts 6, 7 although when these slip sideways as is shown in Figure 2, cannot introduce themselves between the cylinders and the plates 1.

5 On using belts of greater width than the normal as occurs for example on equipping with high draught mechanisms certain types of mule frames of three or four ends per cylinder (Bolton type) or in the speed or fly frames there occurs that these very wide belts which revolve under pressure on the cylinder, have a great tendency to slip 10 towards one side or another and exert a considerable strain on the plate of the framework, in such a manner that sometimes they even bend or deform the plate in which case the belt gets under the plate and prevents the proper working of 15 the machine. In order to absolutely prevent this happening there is adopted the arrangement shown in Figures 3 and 4 in accordance with which the plates 1 present on their interior face and on the edge of the cut by which they fit on the throat 4 of the lower cylinder 2, a projecting 20 part or flange 8 curved in such a way that this adapts itself on the collar 4 of the cylinder, the thickness of said flanges corresponding to the 25 difference in radius of the part 4 and the part 2 30 of the cylinder.

These flanges 8 contribute to fit the guiding device on the cylinder but their principal object is that on the lower belt 6 sliding sideways as is shown in Figure 4, the edge of the belt remains 35 on the flange 8 and as this forms an integral part of the plate 1 there is no possibility of the belt bending itself and getting between the plate 1 and the cylinder 2.

40 In practice it is not necessary to arrange these flanges 8 except for the lower belt, for as the top cylinders are loose and only act by pressure on the straps or belts, the difference in diameter between the thick part of the cylinder and the throat or reduced part of the same may be made 45 sufficiently big to prevent the belt introducing itself between the cylinder and the plate. On the other hand in the lower cylinders as all the cylinders of the machine are joined together forming a bar and receive their movement from one of the heads of the machine it is not possible 50 to reduce very much the diameter of the throats 4 in order to avoid the danger of breaking or twisting same.

55 The union of the two side plates is effected by

means of a cross piece 9 arranged in the back part of the framework, as is seen in Figures 5 and 6. This joining piece 9 is of a relatively big height and has on the top a cut or notch 10 which remains precisely in front of the contact line 11 of the two belts 6, 7. This cut 10 is prolonged towards each side up to a certain distance from the corresponding side plate 1 and the vertical edges 12 of this cut constitute stops which limit the transversal movement of the sliver on entering the pair of endless belts. In this way there is avoided that the sliver in its transversal movement may introduce itself in the small spaces remaining between the plates and the body of the cylinders and in this way stopping the working of the mechanism.

This union of the two plates 1 is consolidated by arranging in the lower part of the plates another crosspiece 13 as is seen in Figures 7 and 8. 20 This crosspiece 13 is arranged in such a way that the outer surface of the lower belt rubs strongly against the edge of the crosspiece which in this manner acts as a belt cleaner, as the fluff and loose fibres which have adhered to the 25 belt separate themselves by this rubbing against the cross piece 13 and meet on the back face of same as is seen in Figure 7 until they fall on the table or rail of the machine from whence they are withdrawn by the operative.

30 In the present application the bar or crosspiece 13 is necessarily provided with a sharp edge against which the belt rubs, as the rubbing of the belt against this sharp edge is precisely what causes the fibres adhered to the belt to fall 35 from the same, and to accumulate behind the crosspiece 13. With reference to this action I desire to have it noted that the fibres do not accumulate in front of the bar 13 as it appears they ought to do, but precisely behind the bar in the 40 manner shown in Figure 7. This is an effect which as yet is not well explained, but the result undoubtedly proved in practice that with this crosspiece 13 the lower belt is always kept clean, and that the fibres which had adhered to the 45 lower belt tend to accumulate behind the crosspiece 13.

This arrangement makes it unnecessary to use 50 clearers for the lower belts which have always resulted very difficult in manipulation for re-moving and cleaning.

The arrangement described of this crosspiece 13 has in addition other advantages when one thread is obtained from two rovings. It often happens in such a case that one of the two rovings breaks whilst the other continues being spun 55

and the result is the production of a thread the half of the thickness it is desired to obtain. If revolving underclearers are used when one of the rovings breaks this accumulates around the clearer and as these clearers are not easily visible it is difficult for the operator to note that one of the rovings has broken. On the other hand on using as a clearer the crosspiece 13 in the way described, the broken roving is efficiently separated from the lower belt and falls upon the rail of the machine and in this way the operative immediately notes that the roving has broken.

This arrangement of the cleansing crosspiece 13 is not necessary for the top belts as these are cleaned already by the top clearers and as these are in full view of the operative any accumulation of roving is easily seen on them.

I claim:—

1. In a guiding device for the endless belts of drawing mechanisms having upper and lower cylinders provided with diametrically reduced throat and enlarged portions, the arrangement of two side plates which are mounted adjacent to the throat portions of the lower cylinders that move the belts, and are likewise placed close to the enlarged portions of these cylinders, and the arrangement on the interior face of each side plate, of a curved flange shaped in such a way that it adapts itself on the throat of the lower cylinder and whose top edge remains at the same level as the surface of the central part of the cylinder in such a way that if the lower belt slips sideways it passes over this flange and absolutely prevents same introducing itself between the plate and the cylinder.

2. In a guiding device for the endless belts of drawing mechanisms having upper and lower cylinders provided with diametrically reduced throat and enlarged portions, the arrangement of two side plates which are mounted adjacent to the throat portions of the lower cylinders that move the belts, and are likewise placed close to the enlarged portions of these cylinders to prevent the belts slipping between the cylinders and the side plates, and the employment of a supplementary crosspiece between the two side plates, arranged in the lower part of these plates, the said crosspiece having a downwardly projecting rear wall with its outer ends bent slightly whereby the upper end of the crosspiece presents a sharp edge to engage the outer face of the lower endless belt and to coact with the downwardly projecting wall to keep the lower belt free from fibres.

FERNANDO CASABLANCAS, JR. 55
